[57] CLAIM

The ornamental design for an awning clamp, as shown and described.

DESCRIPTION

FIG. 1 is a perspective view of an awning clamp embodying my design;

FIG. 2 is a left side elevational view of the awning clamp as shown in FIG. 1, the right side elevational view being a mirror image thereof;

FIG. 3 is a top plan view of the awning clamp as seen in FIG. 1;

FIG. 4 is a bottom plan view of the awning clamp as seen in FIG. 1;

FIG. 5 is a front elevational view of the awning clamp as seen in FIG. 1; and,

FIG. 6 is a rear elevational view thereof.

The partially obscured and undisclosed surfaces of the design follow the contours of the sides shown.
